UNITED STATES PATENT OFFICE.

CHARLES HATZFIELD, OF MINERAL WELLS, TEXAS.

WINDOW STRUCTURE.

1,052,721.

Specification of Letters Patent. Patented Feb. 11, 1913.

Application filed April 12, 1911. Serial No. 620,759.

To all whom it may concern:

Be it known that I, CHARLES HATZFIELD, a citizen of the United States, residing at Mineral Wells, in the county of Palo Pinto and State of Texas, have invented certain new and useful Improvements in Window Structures, of which the following is a specification.

My invention relates to window structures and has particular reference to such devices including upper and lower sash frames which may be raised and lowered and swung or tilted.

An important object of this invention is to provide a window structure of the above character, which is simple in construction, easy to operate and cannot be opened from the exterior of the building.

A further object of my invention is to provide novel means to lock the sash frames in their closed position.

A further object of my invention is to provide novel means to hold one of the sash frames in adjustment at different angular positions.

Other objects and advantages of this invention will be apparent during the course of the following description.

In the accompanying drawings forming a part of this specification and in which like numerals are employed to designate like parts throughout the same, Figure 1 is an inner side view of my improved window frame, Fig. 2 is a detail of a device for holding the upper sash frame in adjustment at different angular positions, Fig. 3 is a similar view of a latch to lock the adjacent ends of the upper and lower sash frames, taken on line $\alpha-\alpha$ of Fig. 1, Fig. 4 is a transverse vertical sectional view taken on line 4—4 of Fig. 1 and looking in the direction of the arrow, the upper sash frame being swung inwardly, Fig. 5 is a similar view, showing the sash frames in different positions, Fig. 6 is a perspective view of one of the tracks for the upper sash frame, and, Fig. 7 is an enlarged sectional view taken substantially on the line 7—7 of Fig. 1.

In the drawings wherein is illustrated a preferred embodiment of my invention, the numerals 1 and 2 designate vertical sides of the window frame, which are connected at their lower ends with a sill 3, and an outer sill 4, having engagement with the inner sill, as shown.

The numeral 5 designates the upper end portion of the window frame.

Movably mounted within the window frame are upper and lower sash frames 6 and 7, carrying sections of glass 8 or the like. Each of the vertical sides 1 and 2 is provided upon the inner face thereof and near its upper end with a metallic track or guide, comprising a plate or body portion 9 which is vertically disposed and carries an outwardly extending horizontal portion 10, at the lower end thereof. The plate 9 may be secured to the vertical side of the window frame by means of screws 11 or the like, and such plate is preferably sunk within said vertical side to be flush with the inner face thereof. The plate 9 and the portion 10 thereof are provided with a substantially L-shaped slot 12 formed therethrough, which is vertically disposed for the greater portion of its length and extends outwardly at its lower end and in a substantially horizontal position. The track or guide way further comprises a substantially L-shaped flange 13 carried by the plate 9 and the portion 10 and the same may preferably be formed integral therewith. The flange 13 fits within a suitable slot or opening formed in the vertical side of the window frame. It is to be understood that the two tracks or guide ways secured to the sides 1 and 2 are alike and are positioned in alinement. Each of the portions 10 of the tracks or guide ways is provided with an upstanding ear having an opening formed therethrough for pivotally receiving a pin 14, which is rigidly connected with the lower end of the upper sash frame 6. The sash frame 6 is thus pivotally supported and is capable of being oscillated inwardly but is prevented from oscillating outwardly by virtue of a lining 15.

The lower sash frame 7 has an eye bolt 16 rigidly connected to the upper end thereof and upon each of its sides, which eye bolt is disposed to operate within the slot 12 of the track or guide way. A cord 17 is secured to the eye bolt 16 and extends upwardly to be trained about a pulley 18. This cord has connection with a weight (not shown) as is well known.

When the upper and lower sash frames 6 and 7 are in their closed positions they are arranged one above the other, as shown in Fig. 3. The upper end of the sash frame 7

is provided with an opening formed therein for receiving a stem 19, to the outer end of which is secured a knob 20. The sash frame 7 is further provided with an opening 21, within which is disposed to oscillate a plate 22, which is rigidly connected with the stem 19 and adapted to move into and out of an opening 23 formed in the lower end of the sash frame 6.

10. From the construction of the above referred to parts, it is obvious that means are provided to lock and unlock the adjacent ends of the sash frames 6 and 7. The lower end of the sash frame 6 is provided upon its 15 outer side with a strip 24, which is rigidly secured thereto and positioned to overlap the line of engagement of the sash frames 6 and 7, as clearly illustrated in Fig. 3. The sash frame 7 is provided upon its lower end 20 and upon the inner side thereof with a lift member 25. Suitably secured to the upper end portion 5 of the window frame, is a stationary support 26, upon which is fulcrumed a lever 27, having connection at its 25 outer end with a cord or other flexible member 28, which extends downwardly to engage a pulley 29, as clearly illustrated in Fig. 8. The cord 28 has its lower end attached to a reciprocatory stem 30, which is 30 slidably mounted within an opening formed through the side 2. The stem 30 carries at its outer end a knob 31 and said stem also operates through an opening formed in a plate 32. The inner end of the pivoted 35 lever 27 is apertured to receive a bolt 33, carrying a nut 34 upon its upper end and a head 35 upon the lower end thereof. This head operates through an opening formed in a plate 36 and is adapted for movement 40 into and out of a socket 37, which is carried by the upper end of the sash frame 6. The bolt 33 is slidably mounted within an opening formed through a stationary bracket 38, connected with the end piece 5. A compressible coil spring 39 serves to urge the 45 head 35 downwardly into the socket 37. From the description of the above referred to parts, it is obvious that means are provided to lock the upper sash frame 6 in its 50 closed position and adapted upon proper operation to release the sash frame to allow the same to oscillate inwardly.

The vertical side 1 is provided upon its inner wall with a plate 40 suitably secured 55 thereto and arranged to be flush with the inner face of the wall. This plate is provided with upper and lower spaced openings for receiving reciprocatory pins 41 and 42, which are pivotally connected with a lever 43, fulcrumed upon a stationary support 44. By pressing either of these reciprocatory pins inwardly until the same is flush with the plate 40, the other will be forced outwardly and disposed in the path 60 of travel of the upper sash frame 6. From

the construction of the above referred to parts, it is obvious that means are provided for holding the upper sash frame 6 in adjustment at different angular positions.

In Fig. 5 the plate 9 of the track or guide 70 way is shown as being provided with a plurality of cut-out portions or recesses 45, which are spaced from each other, as shown, and adapted for reception of the eye bolt 16. When this structure is employed the sash 75 frame 7 is not connected with a weight but is held in different vertical positions by the eye bolt fitting within a selected one of the openings 45.

When the sash frames are in their closed 80 positions they are arranged directly one above the other and are locked in such positions by the means hereinabove described. When it is desired to swing the upper sash frame 6 inwardly, the latch device, including the knob 20 is manipulated to unlock the lower sash frame from the upper one, subsequent to which the knob 31 is drawn outwardly whereby the head 35 is moved out of the socket 37. The sash frame 6 is 85 then capable of being oscillated inwardly until such movement is limited by the engagement of the sash frame 6 with either of the pins 41 and 42. Assuming that the sash frames 6 and 7 are in their closed positions, 90 the frame 7 having been freed from locked engagement with the frame 6, may have the upper end thereof moved inwardly and subsequently upwardly. It will thus be seen that the sash frame 7 may be disposed in 100 different vertical positions. The sash frame 7 may also be oscillated inwardly.

I wish it understood that the forms of my invention herewith shown and described are to be taken as preferred examples of the 105 same, and that certain changes in the shapes, sizes, and arrangements of parts may be resorted to without departing from the spirit of the invention or the scope of the subjoined claim.

Having thus fully described my invention, I claim:—

The combination with a window frame, of an upper sash frame disposed therein, the window frame having its vertical side 115 walls provided with L-shaped openings which are disposed inwardly of the upper sash frame with their lower horizontal portions extending outwardly to be disposed below and suitably spaced from the lower 120 end of the upper sash frame, L-shaped metallic loop tracks adapted to fit snugly within the L-shaped openings and be thus securely held in place, flat plates formed upon the outer longitudinal edges of the loop L-shaped tracks, means for connecting the flat plates with the L-shaped tracks, a lower sash frame adapted to assume a position directly below and in alignment with the upper sash frame, projections upon op- 130

posite edges of the upper end of the lower sash frame extending into the L-shaped loop tracks, whereby after the lower sash frame has been moved horizontally inwardly the same may be elevated and swung in a vertical plane with relation to the upper sash frame, said plates being provided upon their outer portions with respect to the upper sash frame with spaced openings to

receive the rods, whereby the lower sash frame may be supported in different vertical positions.

In testimony whereof I affix my signature in presence of two witnesses.

CHARLES HATZFIELD.
